BRAIDING MACHINE

John Dunn, Mountainside, N. J., assignor to
Titeflex, Inc., Newark, N. J., a corporation of
New Jersey

Application June 27, 1941, Serial No. 399,976

3 Claims.

(Cl. 87—32)

This invention relates to improvements in braiding machines, and method of operating, for fabricating tubular braided structures either in the form of a covering for an elongated body such as a tube or conduit, or for fabricating braided cords and the like.

The invention relates more particularly to the well known "Maypole" type of braiding machines and is especially intended for use in braiding a covering of metal strips upon the exterior of a flexible metal tube, such structure of tube with a braided covering being shown and described in the Brinkman Patent No. 1,340,818 issued May 18, 1920, with special reference to Fig. 5 of that patent. The invention is, however, applicable to any structure of braiding machine and may be employed in connection with any use to which it is suitable.

A usual construction of the "Maypole" type of braiding machine comprises a horizontal deck or track plate provided with grooves, slots or tracks extending about the axis of the machine and in which the bobbin carriers are guided around the axis of the machine. There are usually two guide-ways in the deck or track plate, leading in a tortuous or sinuous course around the central axis of the machine and crossing each other at regular intervals. Two sets of bobbin carriers are traveled in opposite directions in the tracks or guide ways, to cause the carriers to pass inwardly and outwardly around each other to interlace their strands, strips or filaments in accordance with the well known method of a "Maypole" dance. A strip, strand or filament extends upwardly from the bobbin on each of the carriers to a point adjacent to the vertical axis of the braiding machine, and by reason of the interlacing action as described a braid is formed about the said axis. If it is desired to apply a braid to the exterior of a tube or other similar elongated body, the tube or body is caused to pass upwardly at the axis of the braider at a speed suitably proportioned to the braiding operation when the braid will be formed upon the exterior of the said tube or body.

One of the main objects of the invention is to provide a machine of the character as indicated which shall be practically capable of greatly increased speed and therefore of productive capacity.

A further object of the invention is to reduce the noise of operation of such machines.

A further object of the invention is to increase the durability and the life of such machines by reducing the wear of the parts thereof.

A further object of the invention is to provide means for accomplishing the desired objects which shall be readily applicable to braiding machines now in common use.

5 A further object of the invention is to provide a machine of the character described wherein the guides for the strip or filament leaving the bobbin shall freely adjust itself to conditions whereby the strip shall enter properly into the braid.

10 A further object of the invention is to reduce the wear on the strip guiding means.

A further object of the invention is to provide a new and improved method of operating a braiding machine.

15 Other and ancillary objects of the invention will appear hereinafter.

In the accompanying drawings which illustrate the invention—

Fig. 1 is a top plan view of a machine, partly 20 in section and with some parts omitted, embodying the invention, of apparatus and by which the method may be carried out;

Fig. 2 is a section, on an enlarged scale, on the line 2—2 of Fig. 1, such section extending partially across the machine, the other side of the machine being of similar construction, certain of the parts being broken away;

Fig. 3 is a side elevation, on an enlarged scale, 25 of a bobbin-carrier, adjacent parts being broken away and certain parts being shown in section;

Fig. 4 is a side elevation of a length of metal tube with a braided covering of metal strips, the same being the product of the machine of Figs. 1, 2 and 3; and

30 Fig. 5 is a view similar to and on the same scale as Fig. 2, showing a modified construction of braiding machine embodying the invention of apparatus and by which the invention of method may be carried out.

35 Referring to the drawings and first to Figs. 1, 2, 3 and 4, the apparatus comprises a deck or track plate comprising an inner ring 1 having equi-distant star points 2 and an outer ring 3 having star points 4 opposite the star points 2,

40 and intermediate irregularly-shaped plates 5 usually called "quoits." The quoits 5 are arranged centrally within the spaces between the points 2 and 4 and have their edges lying contiguous to and spaced slightly apart from the scalloped edges of rings 1 and 3 whereby to provide the sinuous slots, tracks or guide-ways 6 and 7 for the shoes 15 of the bobbin carriers, which slots intersect at the crossing points 8.

45 The rings 1 and 3 and the quoits 5 of the deck or track plate are arranged in a horizontal plane.

The ring 3 is supported by, secured to and spaced from the lower flat, annular plate 9 by a series of bolts 10. Each of the quoits 5 is supported by, secured to and spaced from the lower plate 9 by a bolt 11 and the inner ring 1 is supported by, secured to and spaced from the plate 9 by a series of bolts 12. Each of the bolts 11 is locked against turning in the quoit 5 or the plate 9 by keys 13 and 14.

Rotatably mounted upon each of the bolts 11 is a spur gear 16 and a horn gear 17, the gears 16 and 17 being fixed to each other. One of the spur gears is driven by intermeshing with another spur gear, 18 fixed upon the shaft 19, through spiral gears 20 one of which is fixed on the shaft 19, and the other upon a driving shaft 21 which may be driven from an electric motor or other suitable source of power, this driving shaft 21 being rotatably mounted in a bracket 22 which is secured by bolt 24 to the bottom 23 of an oil pan which is supported upon the beams 25 and 26 which may be mounted in any suitable manner.

Also the bolts 10, 11 and 12 extend through the bottom 23 of the oil pan so that the lower plate 9 and all of the parts secured to it by the bolts mentioned will be secured to the pan bottom 23 by nuts on said bolts on the outer side of the pan bottom. Leakage from the pan through the bolt holes may be prevented by gaskets 27, 28 and 29 encircling the bolts 10, 11 and 12 respectively and inserted between the bottom plate 9 and the pan bottom 23.

Each of the horn gears comprises a circular plate 30 having the recesses 31 and 32 upon diametrically opposite sides of the plate and within these recesses is embraced projections or horns 33 and 34 of circular cross section, extending downwardly from the bobbin carriers, there being two bobbin carriers (moving in opposite directions about the center of the apparatus) for each horn gear. There is a spur gear, as 16, corresponding to each of the horn gears and each of the gears as 16 meshes with its adjacent similar gears so that all such spur gears about the apparatus are geared together.

Fixed to each bobbin carrier beneath the deck or track plate is a flange 35 which prevents undue tipping or upward movement of the bobbin carrier. Each bobbin carrier has a frame comprising a base portion 36 fixed to a shoe 15 travelling within a guide slot of the track plate, and uprights 37 and 38, the base 36 overlapping the edges of the guide slot in the deck or track plate.

The bobbin 39 for the filament or strip 40 is rotatably mounted (see Fig. 3) being fixed upon a shaft 41 rotatably mounted in the uprights 37 and 38. The bobbin is held against turning by a ratchet wheel 42 fixed to the shaft 41 held against movement by the pawl 43 pivoted on the bobbin carrier frame and having its nose 44 urged toward the ratchet wheel by a spring 45 acting upon the tail 46 of the pawl. The strip 40 passes from the bobbin over a pulley 47 rotatably mounted on the carrier frame and thence passes over a pulley 48 rotatably mounted in an arm 49 pivoted in the carrier frame at 50, a spring 51 pressing the arm so as to force the pulley 48 against the strip 40 to hold it taut.

With the bobbin parts in the position as shown in Fig. 3, the bobbin being held stationary by the pawl and ratchet 43 and 42, the slack in the strip will be taken up as the braiding operation proceeds by the spring-pressed pulley 48 and arm 49 which will be forced upwardly against the tension of the spring 51 until the nose 52 on the arm

49 comes against the tail of the pawl 46 throwing the nose 44 of the pawl out of engagement with the ratchet wheel 42 against the tension of the spring 45. The bobbin being then free to move, 5 the spring 51 will force the arm 49 and pulley 48 downwardly toward the position as shown in Fig. 3, the bobbin unwinding to provide the slack. When the nose 52 has left the tail 46 of the pawl, 10 the nose 44 of the pawl will be again thrown in engagement with the ratchet wheel and arrest the bobbin. The slack will then again be taken out of the strip by the braiding operation which will operate to again raise the pulley 48 and arm 49 against the spring 51, and finally the ratchet 15 wheel will again be released as before described and the operation will be repeated so long as the machine is in operation.

In order to prevent too sudden operation or over-running of the bobbin when released, a 20 brake is applied thereto by means of the brake arm 53 pivoted to the base 36 at 54 and drawn against the ratchet wheel by a spring 53.

The strip 40 passes to the braid 72 on the tube 65, over a guide roller 56 rotatably mounted upon the bushing 57 rotatably mounted in the annular support 58 on the frame of the bobbin carrier.

In order that the pulley 56 may freely swing it is necessary that the sleeve or bushing 57 should readily turn so that the strip may, with changing positions of the bobbin carrier with relation to the braid, adjust itself so that the strip will be properly applied to and lie in the braid. For this reason the sleeve 57 is mounted upon ball bearings 59. Also if the strip 40, which passes through the bushing 57, should, in any of its positions, draw against the bushing the rotation of the bushing would be interfered with and the parts would become worn. It is, therefore, provided in the present machine that the parts shall be so proportioned and arranged that the strip 40 shall, in none of its positions, come against the sleeve 57 so that the guide pulley 56 may readily adjust itself without interference. In previous devices of this character the strip or filament in some or all of its positions draws against the sleeve through which it passes, with disadvantageous results as indicated.

The oil pan having the bottom 23, has the side 60 spaced from the deck and bottom plate 9, the body or bath of oil 61 being applied to the pan from any suitable source through an inlet 62 and the pan has a draining opening 63 in its bottom which may be removably closed by a screw plug 64.

In order that the conduit 65 upon which the braid is to be placed may pass vertically upward through the center of the machine, a hole 66 is formed in the center of the pan, and in such hole is secured in a fluid-tight manner the end of the tube 67 which extends upwardly to a distance sufficient to prevent the oil 61 from splashing over the upper edges thereof. This tube forms the inner wall of the pan and is spaced from the deck and bottom plate 9. Oil is filled into the pan to such level as will, by submersion, or by splashing or washing when the oil bath is agitated by the moving parts, cause an abundant supply of oil to be substantially continuously afforded to the upper side of the track plate where it will lubricate all bearings with the upper surface of the track plate and within the track slots thereby lubricating the same, whereby noise incident to the operation thereof is reduced, the bearing surfaces are thoroughly lubricated, whereby wear and friction is reduced, and the speed of operation may

be greatly increased. This bath will be of sufficient depth to immerse the gears and driving parts beneath the deck or track plate and within the pan, whereby all the bearings thereof will be thoroughly lubricated, the noise of operation reduced and greatly increased speed of operation of the apparatus may be realized. Good results have been obtained by making the surface of the oil bath substantially on a level with the bottom face of the deck.

It will be observed that the oil pan has an open top whereby the operation and condition of the parts may be viewed at all times and the oil may freely splash or wash to the upper surface of the track plate. In order, however, that the oil may not splash out of the pan the sides of the pan should be made sufficiently high so as to prevent this. The sides of the pan should therefore be at least as high as somewhat above the deck or track plate and may be considerably above the bottom so as to surround the same and thereby insure against splashing of oil out of the pan and form a guard against foreign objects which otherwise might intrude laterally to interfere with or injure the apparatus. An auxiliary upper portion 68 of the pan side may be secured to the top of the side 60 by a strip 69 soldered to the top pan section 68 and having its lower portion telescoping within the pan wall 60, the upper section 68 being secured to the lower section 60 of the pan wall by wing-bolts as 10 distributed around the periphery of the pan wall. Of course the joint between the upper and lower sections of the oil pan wall may be made fluid-tight in any suitable manner as by placing a gasket 71 between the sections. By thus making the top portion of the oil pan wall removable, the wall may be made high enough to prevent the splashing of the oil out of the pan and to form a guard as referred to, and at the same time the upper section may be removed when desired to inspect, repair or adjust the bobbin or bobbin carriers without awkwardly observing or reaching down over the high top edge of the pan wall if indeed the desired objects could, under all circumstances, be accomplished in that way.

Leakage of oil from the pan about the shaft 19 is prevented by a stuffing box 13 fixed to the bottom of the pan in a fluid-tight manner. The spiral gears 20 interengage so as to prevent any undue axial movement of the shaft 19 so that the stuffing box 23 may be of simple and well-known construction with no provision for a thrust bearing for limiting the longitudinal movement of the shaft 19. To inspect or repair the parts between the deck or track plate and the lower annular plate 9, the oil may be drained out through the opening 63 and a door or doors as 74 may be provided in the pan wall opposite the space between the deck and lower plate as referred to. Such a door may be secured to the pan wall in any suitable manner and suitable gaskets or other means provided for rendering the closure fluid-tight when the door is closed.

In the operation of the machine the metal conduit 65 without the braid is passed upwardly through the tube 67 by any suitable means (not shown) and the flat, metal strips 40 of the braid 72 are applied thereto after the fashion of the well-known "Maypole" braiding machine, the bobbin carriers with their bobbins travelling about the metal conduit 65 at the center of the machine, in sinuous intersecting paths whereby the braid 72 is formed upon the tube 65 as is well understood in connection with braiding machines

of this type. The movement of the machine parts in this operation agitates the oil of the oil bath and insures the application of an abundant supply of oil to the upper part of the deck or track plate and at the same time the pan, having an open top, the condition and operation of the apparatus can be readily observed and controlled at all times. Also the flat strip will be properly laid into the formed braid, the final 10 guiding means for the strip before it enters the braid being readily self-adjusting and without danger of undue wear. It will also be observed that the oil pan may be readily applied to an existing braiding machine without disorganizing such machine.

Referring now to the construction of Fig. 5, the apparatus is the same as that described in connection with Figs. 1 to 4 except that the oiling provisions are different. In the structure of Fig. 5, the oil pan has the bottom 75 from which upwardly extend the side walls 76 and in the center of the bottom is an opening in which is secured in a fluid-tight manner, the end of the tube 77 through which the tube 65, to which the braid is to be applied, passes.

About the tube 77 is formed a gutter 78 into which oil may drain from the bottom of the oil pan, such gutter being fluid-tight and provided with one or more outlet pipes 79. Also a gutter 80 for receiving drawings from the bottom of the pan is formed at the outer edge of the bottom 76 and such gutter is fluid-tight except for one or more drain pipes 81 communicating therewith.

To facilitate the examination and repair of the parts in the space between the deck plate and the lower plate 9' corresponding to the lower plate 9 of Figs. 1 and 2, one or more openings, opposite the said space in the said wall 76 are provided, each of such openings being removably closed by closures 82 detachably secured in a fluid-tight manner to the wall 76.

An inclined wall 83 extends entirely about the deck or track plate and the tube 77, such inclined 45 wall being secured in a water-tight manner at its inner and upper portion to the pipe 77 and at its lower and outer portion in a water-tight manner to the disk or track plate. Also the inclined wall 84 which extends entirely about the 50 track plate and the wall of the oil pan is secured in a fluid-tight manner at its upper and outer edge to the wall 76, and at its inner and lower edge to the deck or track plate.

Adjacent to the wall 76 and to the upper end 55 of the wall 84 is an oil pipe 85 which extends entirely about the wall 76 and is provided with a suitable number of, and suitably distributed, outlet openings as 86, oil being supplied to the pipe 85, from any suitable source by an inlet pipe 87.

Also surrounding the tube 77 adjacent the upper end of the inclined wall 83 is an oil pipe 88 having a suitable number of outlets 89 suitably distributed, and oil may be supplied to the 65 pipe 88 through an intake pipe 90.

The oil from the outlets 86 and 89 will flow down the inclined walls 83 and 84 on to the top of the deck or track plate lubricating all bearings in connection therewith and, percolating 70 down through the sinuous slots for the bobbin carriers, will lubricate the gears and bearings below the deck or track plate and will finally reach the bottom and collect in the gutters 78 and 80 whence it will be drained off through the 75 drain pipes 79 and 81. A continuous flow of oil

from the outlets 86 and 89 will cause a continuous flow of lubrication on the top of the deck plate and down through the various bearings and gears to the gutters 78 and 80 whereby the whole will be thoroughly lubricated thus decreasing the wear while increasing the efficiency and longevity of the parts as well as permitting an increase in the speed of operation whereby the output of the product of the machine in a given time may be greatly increased.

While the invention has been illustrated in what are considered its best applications it may have other embodiments and the method may be varied and practiced by other means than that set forth, without departing from its spirit. The invention is not, therefore, limited to the structures shown in the drawings.

What I claim is:

1. In a braiding machine the combination with a plurality of bobbin carriers, of an annular deck having intersecting sinous track slots in which said carriers are guided, each of said carriers having a horn extending below said deck, horn gears below said deck and adapted to engage said horns to move said bobbins along the said sinous track slots, intermeshing driving gears fixed respectively to said horn gears, a flat, annular bottom plate, means for securing said bottom plate and said deck together, said horn gears and said intermeshing gears being rotatably mounted in said deck and bottom plate and an oil pan having a flat, annular bottom beneath said bottom plate, said pan bottom extending beyond the inner and outer edges of said bottom plate, and said pan having an outer side secured to the outer edge of said pan bottom and extending above said deck and said pan having an inner, tubular side wall through which the body receiving the braid may pass, said tubular side wall being secured to the inner edge of said pan bottom, said inner, tubular wall extending through both said bottom plate and said deck, said pan being substantially liquid-tight around said deck, said oil pan having an open top.

2. In a braiding machine the combination with a plurality of bobbin carriers, of an annular deck having intersecting sinous track slots in which said carriers are guided, each of said carriers having a horn extending below said deck, horn gears below said deck and adapted to en-

gage said horns to move said bobbins along the said sinous track slots, intermeshing driving gears fixed respectively to said horn gears, a flat, annular bottom plate, said horn gears and said intermeshing gears being rotatably mounted in said deck and bottom plate and an oil pan having a flat, annular bottom beneath said bottom plate, said pan bottom extending beyond the inner and outer edges of said bottom plate, and said pan having an outer side secured to the outer edge of said pan bottom and extending above said deck and said pan having an inner, tubular side wall through which the body receiving the braid may pass, said tubular side wall being secured to the inner edge of said pan bottom, said inner, tubular wall extending through both said bottom plate and said deck, said pan being substantially liquid-tight entirely around said deck, and common means for securing said bottom plate, deck and said pan bottom together.

3. In a braiding machine the combination with a plurality of bobbin carriers, of an annular deck having intersecting sinous track slots in which said carriers are guided, each of said carriers having a horn extending below said deck, horn gears below said deck and adapted to engage said horns to move said bobbins along the said sinous track slots, intermeshing driving gears fixed respectively to said horn gears, a flat, annular bottom plate, means for securing said bottom plate and said deck together, said horn gears and said intermeshing gears being rotatably mounted in said deck and bottom plate and an oil pan having a flat, annular bottom beneath said bottom plate, said pan bottom extending beyond the inner and outer edges of said bottom plate, and said pan having an outer side secured to the outer edge of said pan bottom and extending above said deck and said pan having an inner, tubular side wall through which the body receiving the braid may pass, said tubular side wall being secured to the inner edge of said pan bottom, said inner, tubular wall extending through both said bottom plate and said deck, said pan being substantially liquid-tight entirely around said deck, the said inner and outer pan sides extending upwardly at least to the level of the bobbins.
